KIT FOR OVERHEAD TYPE VALVES

Francis R. Good, Long Beach, Calif.

Application December 18, 1947, Serial No. 792,524

4 Claims. (Cl. 123—90)

(Granted under the act of March 3, 1883, as
amended April 30, 1928; 370 O. G. 757)

1

This invention relates to a valve improvement kit, adapted to be installed in the valve actuating linkage of an overhead valve type engine at the juncture between its cam actuated push rod and the adjacent end of its rocker arm. The improvement kit comprises parts, which when installed, form a hydraulic cushion in the valve opening linkage thereby silencing engine operation and minimizing valve clearance troubles which are experienced as the engine warms up.

The problem of accommodating changing valve clearance as the engine parts warm up is a perplexing one with which engine designers have concerned themselves for many years. Kits of improvement parts are known which may be installed in the valve operating linkages of conventional engines without appreciable modification of the engine. However, as a rule, these kits effectuate a mechanical adjustment of the clearance, whereas it is known that for many purposes a hydraulic cushion introduced in the valve linkage will produce much more effective clearance regulation, with a consequent improvement in silence and operation of the engine.

Hydraulic cushion means for automatically achieving proper valve clearance are also known to the art, but in general these parts either require installation at the factory or require considerable modification in the valve actuating linkage of the engine.

An object of this invention is to provide a kit of valve improvement parts which may be installed in the conventional valve operating mechanism of most types of valve-in-head engines, whereby a hydraulic cushion is formed in the valve actuating linkage with resulting silencing of valve operation and associated benefits which come with improvement in regulation of valve clearance.

It is another object of this invention to provide a kit of improvement parts for the valves of an overhead valve type engine, which may readily and simply be installed on the conventional rocker arm of the engine with the discarding of a minimum of the old parts and with maximum simplicity and speed of installation.

In accordance with the instant invention, the kit comprises a cylindrical member adapted to be mounted around the adjusting stud depending from a conventional rocker arm on an over-

2

head valve engine. This stud is axially slideable within the cylindrical member of this invention, the annular clearance between the stud and the cylinder forming a restricted annular passage for the escape of oil which is compressed within a chamber upon each operating stroke of the valve push rod. The invention also contemplates the provision of means for feeding oil into the chamber, so that in between valve opening operations, the chamber may fill up with oil. Then upon actuation of the valve, through the conventional push rod, the oil is compressed within the chamber and escapes through the restricted annular passage formed between the stud and the cylindrical member installed in accordance with this invention, thereby cushioning the valve action.

Two embodiments of this invention have been illustrated, the first being shown in Figs. 1 through 5 inclusive, wherein:

20 Fig. 1 is a partially sectioned view showing the instant invention applied to the conventional rocker arm of a valve-in-head engine;

25 Fig. 1A is an enlarged fragmentary section showing particularly the critical operating parts of the instant invention;

Fig. 2 is a plan view of the ring forming part of the kit, which ring constitutes the oil-restricting cylinder to be mounted around the adjusting stud;

30 Fig. 3 is a cross sectional elevation of the ring of Fig. 2;

Fig. 4 is a cross sectional elevation of the spring which holds the ring of Fig. 2 in position atop the push rod; and

35 Fig. 5 shows a type of spring compressor which may be used in the installation of the instant invention;

The second embodiment of the instant invention is shown in Figs. 6 through 9 inclusive, wherein:

40 Fig. 6 shows a partially cross sectioned elevation of this embodiment applied to a conventional rocker arm;

45 Fig. 7 shows the rod which forms, with the hydraulic cylinder of the second embodiment, the restrictive oil escape passage;

Fig. 8 is a view of a washer used in the assembly; and

50 Fig. 9 is a view of another washer used in the assembly.

Referring to the illustrations of the first embodiment, 11 designates the conventional hollow, stationary rocker shaft mounted horizontally above an overhead valve type engine. A rocker arm 12 rocks on the shaft 11, the end 13 thereof serving to periodically depress a valve stem (not shown), in the conventional manner. The other end 14 of the arm 12 is disposed above a cam actuated push rod 15. The end 14 is bored vertically and threaded to receive an adjusting stud 16, having at its lower end a hemispherical ball 17 which seats in a socket 18 formed in the head 19 of the push rod 15. Screw adjustment of the adjusting stud 16 is made possible by the provision of a slot 21, the adjustment being secured by a lock nut 22. A perforation 23 in the wall of the shaft 11 registers periodically with a bore 24 in the arm 12, which terminates in a downward passage 25 directly above the ball 17 on the stud 16. In operation, oil under pressure is maintained inside the hollow shaft 11, and intermittently flows onto the ball 17 as the shaft 12 rocks back and forth, thereby maintaining a film of oil between the ball 17 and its socket 18.

The apparatus and operation thus far described constitute the presently known art to which applicant's invention is applied. It will be manifest that with the elements thus far described, each upward thrust of the rod 15 against the stud 16 immediately squeezes substantially all the oil from the hemispherical space (33, Fig. 1A) between the ball 17 and socket 18, inasmuch as there is nothing to restrict escape of the oil. This small space 33 is essential in the operation of the engine to assure that the valve will completely close when the push rod 15 is at its lowest extremity; yet it is desirable in the interest of smooth or quiet operation that this gap, or backlash, be cushioned as the push rod 15 starts its upward thrust.

Cushioning means for this purpose are known in the art as hydraulic valve lifters. The instant invention concerns such a cushioning means as may be quickly and easily installed on a conventional rocker arm as described above.

In accordance with the instant invention, there is provided a ring 26, seated on the upper edge 27 of the head 19 circumjacent the socket 18 and the ball 17. Ring 26 has an upwardly extending cylindrical portion 28, formed around the inner edge thereof, which constitutes an inner wall of internal diameter minutely larger than the encompassed ball 17 (see Fig. 1A). Ring 26 also has a second upwardly extending wall 29 around its outer edge. Wall 29 forms, with wall 28 and stud 16, an annular reservoir 31, which receives oil as it flows down from the passage 25.

A helical spring 32 is compressed between the ring 26 and the overhanging end 14 of the rocker arm 12, thereby maintaining the ring 26 firmly seated around the edge of the socket 18.

Operation

With applicant's device installed in the manner described hereinbefore, the operation is substantially as follows:

At the peak of each upward stroke of push rod 15, the perforation 23 registers with passage 24 and a stream of oil flows from the interior of the shaft 11 to the annular space 31 inside the wall 29. Sufficient oil is passed to overflow the inner wall 28, which also serves to contain the spring 32, so that oil fills the annular space between the outer wall 29 and the lower portion of the adjusting stud 16. At the bottom of the stroke of push

rod 15, the head 19 pulls away from the ball 17, leaving a hemispherical space 33 (Fig. 1A) into which oil flows from the annular reservoir 31 through the restricted annular passage 34, formed between the ball 17 and the circumjacent inner edge of the ring 26. By the time the cycle has reached the point where the push rod 15 again moves up, the space 33 is completely filled with oil.

On the upward stroke of rod 15, the oil in the space 33 is squeezed therefrom, but since the only egress is through the restricted passage 34, a cushion of oil is formed between the head 19 and the ball 17, the oil escaping so slowly through the passage 34 that the operation of the valve is materially quieted and smoothed. By the time the upper limit of the push rod stroke is attained, substantially all the oil has been squeezed from the space 33, thereby assuring full valve clearance when the rod 15 drops.

Inasmuch as valve operation is such that the rod 15 is at the lower extreme of its stroke during a major portion of the operating cycle, there is ample time for oil from the reservoir 31 to seep into the space 33 through the annular passage 34, even though it is impelled only by gravity.

Valve clearance is usually measured between the end 13 of the rocker arm 12 and the top of the valve stem. It is therefore necessary to close space 33 during adjustment. To this end the clamp shown in Fig. 5 is provided, having a lower member 41 adjustably secured to an upper member 42 through a threaded rod 43. A bifurcated toe 44 on the bottom of portion 41 slips under the socket portion of the head 19, and a groove 45 in the upper member 42 seats over the top of the rocker arm 12. A wing nut 46 is then screwed down on the threaded rod 43 to lift the head 19 against the ball 17 and so close the gap 33. Valve clearance may then be checked in the conventional manner, since oil is precluded from filling the hemispherical space and thus cannot affect the clearance.

Modification

A modified form of the instant invention is shown in Figs. 6 through 9, inclusive. In this modification the conventional adjusting stud (16—Fig. 1) is removed from the bore 53 (Fig. 6) and discarded, and replaced by a special fitting 51 having a depending, externally threaded stud portion 52 which is threaded into the bore 53 of the rocker arm. A vertical bore 54 is drilled upwardly through the stud portion 52 and into the body of the fitting 51 for receiving a piston stud 55 axially slidable in the bore 54. At the upper end of the piston stud 55, clearance between the stud and the end of the bore 54 forms a chamber 56, having an offset portion 57 with which communicates a small, vertical bore 58.

The rocker arm 12', already provided with the bored oil passageways 24' and 25', is further bored at 59 to provide a passageway communicating between the upper end of the passage 24' and the lower end of the passage 58. A washer 61, interposed between the fitting 51 and the rocker arm 12', is provided with arcuate slots 62 (Fig. 9) so that the interposition of the washer will not block flow of oil from the passage 59 to the passage 58. At its bottom end the passage 25' is plugged to prevent escape of oil in that direction.

A ball valve 63 seats at the upper end of the passage 58 and is movable within the chamber

portion 57. Ball 63 constitutes a check valve which prevents flow of oil from chamber portion 57 to passage 58, while permitting oil flow in the other direction. Tapped holes are provided in the fitting 51, plugged by screws 64, for providing access to the chamber 57 during fabrication and assembly of the device. A tapped hole immediately above the piston stud 55 receives a set screw 65 secured by a lock nut 66, which serves as an upper limit for reciprocation of the piston stud 55. The adjustment of screw 65 in effect determines the valve clearance. At its lower end the piston stud 55 is provided with the customary ball 67 adapted to reside in a socket in the head of the push rod (see Fig. 1). A helical spring 68, compressed between the ball 67 and the overhanging end of the rocker arm 12', biases the piston stud 55 downward into engagement with its socket. A washer 69 is interposed between the bottom end of the spring 68 and the head 67.

Operation of modification

The above described modification functions substantially as follows. At the clockwise extremity of the oscillation of rocker arm 12', the passage 24' registers with the perforation 23' and oil is fed upwardly through 24', 59, 62, and 58. As the arm 12' pivots counter-clockwise, the upward pressure exerted by the push rod on the piston stud 55 is relieved, allowing the spring 68 to extend the stud 55, thereby maximizing the volume of chamber 56. The oil in the passages 24', 59, 62, and 58 is thus drawn into the chamber portion 57, past the check ball 63, to fill the chamber 56-57 to its maximum capacity.

As the push rod pushes upwardly on the stud 55, the ball 63 covers the passage 58. Back lash between the stud 55 and the arm 12', which in effect corresponds to valve clearance, is thus taken up, for the only way in which the stud 55 can move within the bore 54 is for oil to escape slowly down the sides of the bore around the stud 55 and on to the head 67. This it does at a restricted rate, depending on the closeness of fit of the stud 55 in the bore 54. By the time the stud 55 has been pushed up against the set screw 65, the rocker arm 12' is somewhere near its clockwise extremity. In this way a cushion of oil is continually reinserted in the valve actuating linkage, thereby producing smoother and more silent valve operation.

It will be noted that both modifications of the instant invention are quickly and easily installed on conventional valve-in-head engines, with the replacement of a minimum number of conventional parts. In the case of the first embodiment described, it is necessary to discard no parts whatever from the conventional valve mechanism; while in the case of the modification, only the adjusting stud and its lock nut are discarded.

Two embodiments of the instant invention have been described herein; it will be manifest that this invention may be made and utilized in other suitable embodiments without departing from the spirit and scope thereof as set forth in the appended claims.

The invention described herein may be manufactured and used by or for the Government of the United States of America for governmental purposes without the payment of any royalties thereon or therefor.

What is claimed is:

1. A valve improvement kit adapted to be installed in the valve actuating linkage of an overhead valve type engine at the juncture between

the socketed head on the cam-actuated push rod and the balled end of the depending adjusting stud mounted in the end of the rocker arm, said arm having an oil passage thru which oil is fed onto said balled end, comprising: a ring adapted to seat on the edge of said socketed head circumjacent said balled end, the internal diameter of said ring being minutely larger than the external diameter of the encompassed balled end, thereby forming a restrictive annular escape passage for oil squeezed from between the ball and socket as said push rod pushes said stud upward, and a spring adapted to be mounted around said adjusting stud and compressed between said rocker arm and said ring, thereby to maintain said ring in engagement against said socket head edge.

2. A valve improvement kit adapted to be installed in the valve actuating linkage of an overhead valve type engine at the juncture between

20 the socketed head on the cam-actuated push rod and the balled end of the depending adjusting stud mounted in the end of the rocker arm, said arm having an oil passage thru which oil is fed onto said balled end, comprising: a ring adapted

25 to seat on the edge of said socketed head circumjacent said balled end, the internal diameter of said ring being minutely larger than the external diameter of the encompassed balled end, thereby forming a restrictive annular escape passage for oil squeezed from between the ball and socket as said push rod pushes said stud upward, said ring having an upwardly extending wall around its outer edge forming with said stud an annular reservoir to contain oil flowing down from said

30 rocker arm passage, and a spring adapted to be mounted around said adjusting stud and compressed between said rocker arm and said ring, thereby to maintain said ring in engagement against said socket head edge.

3. A valve improvement kit adapted to be installed in the valve actuating linkage of an overhead valve type engine at the juncture between

40 the socketed head on the cam-actuated push rod and the balled end of the depending adjusting stud mounted in the end of the rocker arm, said arm having an oil passage thru which oil is fed onto said balled end, comprising: a ring adapted

45 to seat on the edge of said socketed head circumjacent said balled end, said ring having an upwardly extending cylindrical portion formed

50 around the inner edge thereof constituting an inner wall of internal diameter minutely larger than the external diameter of the encompassed balled end, thereby forming a restrictive annular escape passage for oil squeezed from between the ball and socket as said push rod pushes said stud upward, and a spring adapted to be mounted around said push stud and compressed between

55 said rocker arm and said ring, thereby to maintain said ring in engagement against said socket head edge.

4. A valve improvement kit adapted to be installed in the valve actuating linkage of an overhead valve type engine at the juncture between

60 the socketed head on the cam-actuated push rod and the balled end of the depending adjusting stud mounted in the end of the rocker arm, said arm having an oil passage thru which oil is fed onto said balled end, comprising: a ring adapted

65 to seat on the edge of said socketed head circumjacent said balled end, said ring having an upwardly extending cylindrical portion formed

70 around the inner edge thereof constituting an inner wall of internal diameter minutely larger than the external diameter of the encompassed

balled end, thereby forming a restrictive annular escape passage for oil squeezed from between the ball and socket as said push rod pushes said stud upward, and a second upwardly extending wall around its outer edge forming with said inner wall and said stud an annular reservoir to contain oil flowing down from said rocker arm passage, and a spring adapted to be mounted around said push stud and compressed between said rocker arm and said ring, thereby to maintain said ring in tight engagement against said socket head edge.
